UNITED STATES PATENT OFFICE.

JOHN LOUCIEN CHESNUTT, OF KANSAS CITY, MISSOURI.

SWIVEL-CASTER.

1,142,930.

Specification of Letters Patent. Patented June 15, 1915.

Application filed August 7, 1914. Serial No. 855,937.

To all whom it may concern:

Be it known that I, JOHN LOUCIEN CHESNUTT, citizen of the United States of America, and resident of Kansas City, Jackson county, Missouri, have invented a new and useful Swivel-Caster, of which the following is a specification.

The object of this invention is to provide an improved construction for a ball-bearing swivel caster.

A further object of this invention is to provide an improved construction whereby a caster wheel may be employed having a maximum diameter relative to the height of the caster, the caster being located directly beneath the load.

A further object of this invention is to provide means for dispensing with the center rivet in a swivel caster, thereby facilitating swiveling chiefly by preventing binding and friction between the contacting surfaces of the wheel bearing part and the attaching plate.

A further object of this invention is to provide an improved construction for a swivel caster having two horizontal rings of bearing balls, the upper ring being designed to take the downward pressure and the lower ring being designed to take the lateral pressure of the load.

My invention consists in the construction, arrangement and combination of elements hereinafter set forth, pointed out in my claims and illustrated by the accompanying drawing, in which—

Figure 1 is a plan of my improved caster, a part of the hidden construction being indicated by dotted lines. Fig. 2 is a front elevation and Fig. 3 a side elevation of the same, each of said views being shown partly in section. Fig. 4 is a front elevation of a modified form of my invention, partly in section. Fig. 5 is a fragmentary sectional elevation of a further modified form of my invention.

In the construction of the device as shown in Figs. 1, 2 and 3, an inner frame is formed of a ring 10 mounted in upright position and having a concaved base or bottom member 11 extending inwardly and downwardly therefrom, said base or bottom being formed with a central, longitudinal rectangular opening 12; and spaced flanges 13, 14 depending from said base or bottom at the side margins of said opening. A wheel 15 is

mounted within the opening 12 of the bottom and the axle 16 thereof is carried in the flanges 13, 14. The axle 16 preferably is mounted in such position that the wheel 15 is somewhat back of the longitudinal center of the opening 12 and of the ring 10. The wheel 15 is of such diameter as to extend upwardly entirely through and preferably project slightly above the upper plane of the ring 10. An outer frame is formed of a ring 17 mounted in upright position outside of and concentric with the ring 10, and a plate 18 mounted on said ring and overlying the ring 10. The plate 17 is formed with spaced, apertured lugs 19 by which it is secured to the plate 18 by means of screws or rivets 20 having their heads countersunk in said plate. The plate 18 is formed with a circular opening 21 in its center to receive the upper portion of the wheel 15. The plate 18 is formed with screw holes 22 by which the device may be attached to any desired load such as a truck, article of furniture or the like. The inner ring 10 is formed with an outwardly projecting, peripheral annular rib or flange 23 intermediate of the upper and lower margins of said ring, and projecting toward but spaced at its outer circumference from the outer ring 17. An upper row of bearing balls 24 is mounted between the plate 18 and annular flange 23 and between the rings 10 and 17. The balls 24 rest on the flange 23 and are contacted by the plate 18, thus bearing and taking away the friction of the load; but said balls are not contacted normally by the inner ring 10, thereby eliminating all lateral friction from said balls. A lower ring of balls 25 is mounted between the rings 10 and 17 and between the flange 23 and an inwardly projecting annular lip or flange 26 on the lower periphery of the outer ring 17. The balls 25 rest on the annular lip or flange 26 and are contacted by the rings 10 and 17, thereby centering the inner frame relative to the outer frame and eliminating the friction from contact thereof; but said balls are not contacted normally by the flange 23, thus eliminating all downward pressure and friction on said balls.

I prefer to construct the inner frame with a reinforcement 27 at the front and rear of the wheel 15, between the ring 10 and base member 11. This reinforcement preferably is beveled, as at 27a, at the forward and rear

margins of the opening 12, to correspond approximately to the curvature of the wheel 15.

Particular attention is called to the fact that the use of the double ring of bearing balls and the elimination of the center rivet commonly employed in swivel casters permits a free and easy swivel or turn of the inner or wheel-bearing frame relative to the outer or load-bearing frame. Any tendency to tip, caused by the passing over an uneven surface, is counteracted by the lower balls 25, which are then contacted by the lower side of the annular flange 23. The setting of the wheel back of the center of the device also facilitates the swivel turn; but in my improvement, owing to the freedom from binding and friction between the wheel-bearing part and the attaching plate, it is not necessary to set the wheel so far back of center in order to induce swiveling; thus further eliminating the binding and friction between said parts due to the tendency to tip. It is well known that in a caster containing a center rivet there is a constant binding and friction between the parts at the point where they are held together by the rivet. This binding is due to the tendency of these two parts of the caster to separate at the rivet, and forward therefrom in front of the caster wheel. Such tendency to separate is due to the caster wheel being axled considerably behind the center in order to compel it to swivel with certainty, and this induces a leverage that causes constant binding as above stated. This tendency to separate, or tip, is especially pronounced during progressive movement of the caster under load, and greatly hinders the swiveling action of the caster. In my construction, the elimination of the center rivet prevents binding during such tendency to tip laterally or forwardly.

Great advantage is derived from employing a wheel of approximately the same diameter as the height of the caster, in that a large wheel runs more easily and is less hampered by running into obstructions or over uneven surfaces. This advantage is attained, in this device, in a caster adapted to be mounted directly beneath the load.

In the construction according to Fig. 4, substantially the same elements as those above described are present, except that the lower ring of balls 25 is omitted and tipping of the device is prevented by contact of the flanges 23^a and 26^a, between which there is a slight space and no contact except during strong tendency to tip, as when the wheel is going over a very rough surface.

In this construction also I have shown the balls 24 placed at a lower level relative to the axle 16, and the wheel 15 projecting through and materially above the plate 18.

It is desirable to set the load as low as pos-

sible relative to the axle in order to prevent the tendency to tip. It is often desirable also to place the attaching plate as low as possible in relation to the height of the caster wheel in order not to increase the height of the load unduly above the floor. In this construction the ring 10^a is foreshortened as to height and the member 11^a has less concavity than in the other construction.

In the construction according to Fig. 5 the inner frame is formed as a disk 11^b with a peripheral flange 23^b at its base, and the flange of the ring 17^a is omitted. The outer periphery of the disk 11^b and the inner periphery of the ring 17^a are slightly concaved to form coacting members of a race containing a ring of balls 24. The top member 18^a of the outer ring preferably is formed integral with the ring 17^a. The balls 24 are inserted into the race through a hole formed in the ring 17^a, which hole is then closed by a screw 28 having its inner end flush with the inner surface of said ring. The flanges of the inner frame, one of which is shown in the drawing and designated by the numeral 13^a, project upwardly through the opening 21, so that the axle 16 is carried above the plane of the balls 24. The axle 16 preferably is carried by special bearers 29 of angle form adapted to be mounted in the inner frame from below, with the wheel and axle, and be secured as by screw 30. The tendency to tip is wholly overcome by having the load attached on a plane below the plane of the axle, or very near thereto. The inner frame is held in place by contact of the balls 24 with the concaved surfaces of the inner and outer frame.

It is to be understood that the modifications shown are merely suggestions as to the various constructions which might be employed, especially with respect to the altitude of the bearing balls, and application of the load, relative to the axle.

I do not desire to be understood as limiting myself to the precise construction and arrangement herein shown and described, as various modifications may be employed without departing from the spirit of my invention.

I claim as my invention—

1. A swivel caster, comprising an outer or load-bearing frame, an inner frame mounted within said outer frame, a wheel journaled for rotation in said inner frame and extending to the top thereof, and bearing balls between said inner and outer frames, said wheel also extending above the plane of said bearing balls.

2. A swivel caster, comprising an outer frame formed with a removable top plate, an inner frame therein, a wheel journaled for rotation in said inner frame, and vertically spaced rows of bearing balls between

5 said inner and outer frames, one row of said balls adapted to receive vertical friction only and the other row of said balls adapted normally to receive lateral friction only, 5 said balls and their races forming the only connection between said inner and outer frames.

10 3. A swivel caster, comprising an outer frame formed with an inwardly projecting annular flange at its base, an inner frame within said outer frame and formed with an outwardly projecting annular flange above the flange of the outer frame, a wheel journaled in said inner frame, a removable 15 plate on the top of said outer frame, and bearing balls between said plate and the flange of the inner frame.

20 4. A swivel caster, comprising an outer frame formed with an inwardly projecting flange at its base, an inner frame therein and formed with an outwardly projecting flange above the flange of the outer frame, a wheel journaled in said inner frame, a removable plate on the top of said outer 25 frame, bearing balls between said plate and the flange of the inner frame, and bearing balls between the flanges of the two frames.

30 5. A swivel caster, comprising an outer frame formed with an inwardly projecting flange at its base, an inner frame therein and formed with an outwardly projecting flange above the flange of the outer frame, a wheel journaled in said inner frame, a removable plate on the top of said outer 35 frame, and bearing balls between said plate and the flange of the inner frame, said plate, flanges and bearing balls forming the only

connection between the inner and outer frames.

6. A swivel caster, comprising an outer 40 frame formed of an upright ring with an inwardly projecting flange at its base, an inner frame formed of an upright ring concentric with the first ring and formed with an outwardly projecting flange above the 45 first flange, said inner ring also being formed with a concaved base member, said base member being formed with a longitudinal opening, flanges projecting downwardly from said base member at the side 50 margins of said opening, a wheel mounted in said opening and having its axle carried by said downwardly projecting flanges, bearing balls between said inner and outer rings, and a removable plate mounted on 55 the top of said outer ring.

7. A swivel caster, comprising an outer frame formed with a ball race, an inner frame formed with a ball race coacting with the first ball race, bearing balls in said races, 60 said inner frame being formed with a longitudinal opening, vertical flanges on said inner frame at side margins of said opening, and a wheel journaled for rotation in said opening and carried by said vertical flanges, 65 said wheel extending above the plane of said bearing balls.

Signed by me at Kansas City, Missouri, this thirtieth day of June, 1914.

JOHN LOUCIEN CHESNUTT.
